[57] CLAIM

The ornamental design for a holder for disposable plastic barrier film, as shown and described.

DESCRIPTION

FIG. 1 is a front elevational view of a combined rolled film and hanging sleeve dispenser showing our new design;

FIG. 2 is a right side elevational view thereof;

FIG. 3 is a rear elevational view thereof;

FIG. 4 is a left side elevational view thereof;

FIG. 5 is a top plan view thereof; and,

FIG. 6 is a bottom plan view thereof.

The broken-line disclosure of rolled film and hanging sleeves in the views are for illustrative purposes only and form no part of the claimed design.
